UNITED STATES PATENT OFFICE.

CHARLES BOOZE, OF BUFFALO, NEW YORK, ASSIGNOR TO M. H. BIRGE & SONS, OF SAME PLACE.

DESIGN FOR WALL-PAPER.

SPECIFICATION forming part of Design No. 21,958, dated November 8, 1892.

Application filed October 10, 1892. Serial No. 448,441. Term of patent 3½ years.

To all whom it may concern:

Be it known that I, CHARLES BOOZE, a citizen of the United States, residing at Buffalo, in the county of Erie and State of New York, 5 have invented and produced a new and original Design for Wall-Paper, of which the following is a specification, reference being had to the accompanying drawing, forming part thereof.

10 The leading features of this design consist of an open basket-like ornament filled with flowers and leaves, a U-shaped scroll ornament arranged below with a spray of flowers and leaves dropping from the basket-like ornament, a small circle arranged underneath the U-shaped ornament, and a festoon of flowers and leaves arranged across the lower portion of said circle and hanging from two scroll ornaments on the sides of the design, as represented in the accompanying drawing. These 20 ornaments are placed at regular intervals over the surface of the paper and are printed in any desired color or colors upon tinted paper of any desired color.

What I claim is—

The design for wall-paper herein shown and described.

Witness my hand this 7th day of October, 1892.

CHARLES BOOZE.
